UNITED STATES PATENT OFFICE.

PAUL GUMBINNER, OF NEW YORK, N. Y.

DESIGN FOR A FABRIC.

SPECIFICATION forming part of Design No. 20,286, dated November 11, 1890.

Application filed October 3, 1890. Serial No. 367,002. Term of patent $3\frac{1}{2}$ years.

To all whom it may concern:

Be it known that I, PAUL GUMBINNER, a citizen of the United States, residing at New York city, in the county and State of New York, have invented and produced a new and original Design for Fabrics, of which the following is a specification, reference being had to the accompanying photograph, forming a part thereof, which represents a plan view of a fabric decorated in accordance with my design.

The essential feature of the design consists of an ornamental figure upon a crape-like background.

The background B consists of closely-grouped irregular dot-like figures, the effect

of the arrangement of said figures being to impart to the background the appearance of crape.

The ornamental figure A is a leaf-like figure consisting of a number of slender tapering curved figures C, appearing to join a stem-like figure D, the uppermost of the figures C seeming to merge one into the other.

I claim—

The design for a fabric, substantially as herein shown and described.

PAUL GUMBINNER.
